UNITED STATES PATENT OFFICE.

SEBIE A. LADD, OF DUANE, NEW YORK.

PAD FOR HORSES.

No. 820,800.

Specification of Letters Patent.

Patented May 15, 1906.

Application filed December 18, 1905. Serial No. 292,227.

To all whom it may concern:

Be it known that I, SEBIE A. LADD, a citizen of the United States, residing at Duane, in the county of Franklin, State of New York, have invented certain new and useful Improvements in Pads for Horses; and I do hereby declare the following to be a full, clear, and exact description of the invention, such as will enable others skilled in the art to which it appertains to make and use the same.

This invention has relation to harness-pads or sweat-pads for horses; and it has for its object to provide a sweat-pad that shall be thoroughly ventilated through and through, so as to absolutely prevent the collar, harness-saddle, or other parts of the harness-trappings from heating, scalding, or otherwise injuring the horse.

The nature of the invention embodies a porous sweat-pad of peculiar structural character in that the holes that are made through the pad from side to side have the longitudinal and transverse lines of quilting-stitches cross the same, thus retaining them in open position and assisting to maintain the portions or squares of the collar between the perforations in a soft "built-up" hump that in use will operate in an appreciable degree and in a bellows-like manner to pump the air into the perforations and allow it to escape so as to keep the under side of the collar cool and thoroughly ventilated at all times.

In collar and other harness pads that are made for summer use the outside and inside coverings are frequently rendered porous by perforating them; but the usually thick padding or stuffing is left imperforate, so that the pad is quite as heating as though the coverings were not perforated.

By my improvements, as before stated, the perforations extend through and through the pad, and steps are provided or taken to keep them open and the pad as a whole in a spongy condition.

The accompanying drawings, which clearly and fully illustrate my improvements, form a part of this specification and are to be referred to as such.

Of the said drawings, Figure 1 is a side elevation of the invention. Fig. 2 is a section on the line 2 2 of Fig. 1. The same letters of reference designate the same parts or features, as the case may be, wherever they occur.

In carrying out my improvements I inclose between two layers of drill-goods *a b* a filling *c* in quantity sufficient for the case in hand and of a quality known as "composite." These three layers may be first basted together and then perforated at short intervals. For instance, in a pad designed for use in connection with collars there may be three rows of perforations *e* run longitudinally of the collar, and the transverse rows may be relatively as wide apart as longitudinal rows. I then quilt the pad with as many lines of 65 stitches as there are rows of perforations, making sure that the rows of quilting-stitches will cross the perforations. This mode of operating builds up soft humps within the lines of stitches and perforations and insures the 70 keeping open of the latter, so as to insure the ventilation and keeping cool of the inside of the collar, as has already been described.

At the point where the shoulder-joint comes and at other points where it may be thought best to have the perforations thicker this may be done by working in fancy figures for the sake of ornamentation. A star, for example, is shown as worked in on the pad shown in Fig. 1.

Hooks *g* are provided at the edge of the sweat-pad for securing the latter to the collar.

What is claimed is—

1. A sweat-pad for horses composed of an outside and inside layer of cloth, as drilling, and an intermediate layer of composite stuffing, said layers being perforated through and through and quilted, the lines of all quilting-stitches crossing in the perforations.

2. A sweat-pad for horses composed of suitable coverings of cloth, and an inner stuffing, said layers or plies being perforated through and through and finished by cross-quilting, the cross-quilting lines of stitches crossing the perforations, as described, and hooks being connected with the outer edges.

3. A sweat-pad for harness perforated through and through, and quilted by lines of cross-stitches, the latter crossing in each perforation.

In testimony whereof I affix my signature in presence of two witnesses.

SEBIE A. LADD.
